UNITED STATES PATENT OFFICE.

SOLOMON KAUFMAN, OF NEW YORK, N. Y.

DESIGN FOR A COLLAR BUTTON.

Application filed September 15, 1926. Serial No. 19,074. Term of patent 14 years.

To all whom it may concern:

Be it known that I, SOLOMON KAUFMAN, a citizen of the United States of America, residing in the city, county, and State of New York, have invented a new, original, and ornamental Design for Collar Buttons, of which the following is a specification, reference being had to the accompanying drawing, forming a part thereof.

In the drawing—

Fig. 2 is a side view thereof.

Fig. 3 is a top view thereof.

I claim:

The ornamental design for a collar button substantially as shown.

SOLOMON KAUFMAN.
